DESIGN FOR A DRESS ENSEMBLE

Sylvia Comolli, New York, N. Y.

Application December 23, 1937, Serial No. 73,824

Term of patent 3½ years

To all whom it may concern:

Be it known that I, Sylvia Comolli, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear waist section of the dress unit is plain.

I claim:

The ornamental design for a dress ensemble, substantially as shown, and described.

SYLVIA COMOLLI.
